UNITED STATES PATENT OFFICE.

CLAUDE C. RUNNER, OF SCHENECTADY, NEW YORK, ASSIGNOR TO GENERAL ELECTRIC COMPANY, A CORPORATION OF NEW YORK.

PRESSURE OPERATING DEVICE.

Application filed October 27, 1920. Serial No. 419,917.

To all whom it may concern:

Be it known that I, CLAUDE C. RUNNER, a citizen of the United States, residing at Schenectady, in the county of Schenectady, State of New York, have invented certain new and useful Improvements in Pressure-Operating Devices, of which the following is a specification.

My invention relates to improvements in pressure operating devices. Although not necessarily limited thereto, my invention has a particular application to pressure operating devices used for operating motor controllers, and when so used it provides improved means whereby abnormal conditions in the motor circuit, such for instance as a failure of voltage, are automatically taken care of in order to protect the motor.

One of the objects of my invention is to provide improved means whereby upon the occurrence of abnormal conditions, the pressure device will automatically operate to establish safe conditions. In carrying my invention into effect in one form, I provide a pressure actuated device which is normally controlled by a pressure controlling valve as long as conditions are normal. In the passages between the pressure controlling valve and the pressure actuated device I provide an electromagnetically controlled valve which is arranged so that when energized it gives complete control of the pressure actuated device to the controlling valve, but when deenergized it governs the pressure actuated device independently of the controlling valve and causes the pressure actuated device to be returned to the initial position. My invention has advantages in that the electromagnetically controlled valve is entirely independent of the pressure controlling valve, and the protective features of the device are in no way dependent upon the effective operation of the pressure controlling valve. A rigid mechanical connection with the pressure controlling valve may be provided, thereby insuring the effective operation of this valve. Advantageous features of simplicity of construction and arrangement are obtained.

In the accompanying drawing I have shown my invention embodied in concrete form for purposes of illustration, the drawing being diagrammatic in some respects in order that an easy understanding of the invention may be had. Referring to the draw-

ing, the pressure actuated device 10 comprising the cylinder 11, piston 12 and piston rod 13 is connected through a crank 14 with the operating lever 15 of a rheostat in the armature circuit of an electric motor having an armature 16 and a shunt field 17. The lever 15 is adapted to cut out sections of the controlling resistance 18-19 when the lever is moved in a counter-clockwise direction, and to reinsert the resistance when the lever is moved in a clockwise direction in response to a downward movement of the piston 12. A pressure controlling valve 20 having two pistons 21 and 22 is adapted to control the passages 23 and 24 leading from the pressure controlling valve to the pressure actuated device 10 for admitting pressure to and exhausting pressure from the said device. The pressure controlling valve is automatically operated responsively to predetermined conditions, such for instance as in response to the pressure exerted on the diaphragm 25. The diaphragm 25 operates the valve 20 through the pivoted scale beam 26, and the link 27 connecting the scale beam with the lever 28 which has one end pivotally connected with the piston rod 29 of the pressure controlling valve 20. The other end of the lever 28 is connected by means of the link 30 with a lever 31 fulcrumed at 32 on a stationary support 33. The right-hand end of the lever 31 is connected by means of a crank 34 with the piston rod 13.

Intermediate the pressure controlling valve 20 and the pressure actuated device 10 is an electromagnetically controlled valve 35 which is arranged so as to give normally the complete control of the pressure actuated device 10 to the pressure controlling valve 20 when the magnet 36 is energized and to operate independently of the pressure controlling valve when deenergized to admit pressure to and exhaust pressure from the pressure actuated device to effect the return of the rheostat lever 15 to a position at which all of the resistance 18-19 is included in the motor armature circuit. This electromagnet valve is provided with three pistons 37, 38 and 39, the arrangement being such that the piston 38 normally closes the passage 40 between the pressure controlling valve and the electromagnet valve, and the piston 39 closes the passage 41 when the valve magnet is energized. It will be observed that on the right-hand side of the electromagnet

valve the passages 23' and 24' are staggered with respect to the similar passages on the left-hand side of the valve, so that when the electromagnet valve is deenergized and drops 5 to its lowermost position, the passages 23 and 24 on the left-hand side of the magnet valve are closed, but the passages 23' and 24' are partly open.

It will be observed that the magnet valve 10 35 is entirely independent of the scale beam 26 and the pressure controlling valve 20, and that there are no mechanical connections between the movable elements of these parts.

There is a rigid mechanical connection, 15 namely, the link 27, between the scale beam 26 and the pistons of the pressure controlling valve 20. The pressure controlling valve operates entirely independently of the magnet 36 and the magnet valve 35 in 20 general.

As thus constructed and arranged, and with the parts in the various positions shown in the drawing, the operation of my invention is as follows: Let it be assumed that the 25 operation of the electric motor causes a fluid pressure to be produced which causes the diaphragm 25 to raise the scale beam 26. This will in turn cause the link 27 to be raised and thereby move the lever 28 a small 30 angular distance counter-clockwise, the lever 28 having its fulcrum point for this motion at 42. The pistons 21 and 22 of the pressure controlling valve 20 will be raised so as to open the passages 23 and 24, thereby admitting 35 pressure to the upper side of the piston 12 through the passage 23, the electromagnet valve 35 and the passage 23', and at the same time connecting the fluid under pressure on the lower side of the piston 12 40 to exhaust through the passage 24', the electromagnet valve 35, the passage 24 and the exhaust passage 43. This will cause the piston 12 of the pressure actuated device 10 to be moved downwardly and thereby rotate 45 the rheostat arm 15 in the clockwise direction, cutting in more of the resistances 18-19 in the armature circuit of the electric motor. This will cause the motor to be operated at a lower speed, and in case the motion 50 of the rheostat arm 15 is continued, the motor armature will be entirely disconnected from the supply circuit and the motor stopped. It will be observed that the downward motion of the piston rod 13 produces a 55 downward motion of the piston rod 29 of the pressure controlling valve in order that the pressure controlling valve will be returned to the position shown in the drawing, thereby stopping further operation of the 60 pressure actuated device. This is brought about through the crank 34 lowering the right-hand end of the lever 31 and thereby raising the left-hand end of the lever 28 through the medium of the link 30, the lever 65 28 this time having its fulcrum point at 44.

This will cause the piston rod 29 to be returned to the position at which the passages 23 and 24 are closed, and the motion of the piston 12 will thereby be arrested.

Assume now that the pressure should fall 70 so that the pressure diaphragm 25 permits

the scale beam 26 to be lowered so as to rest on its lower adjustable stop. This will cause the link 27 to move the lever 28 clockwise, thereby lowering the piston rod 29 and connecting the upper side of the piston 12 of

the pressure actuated device to exhaust through the passage 23', the electromagnet valve 35 and passage 23. The lower side of

the piston 12 will have fluid pressure applied thereto through the passage 24, the electromagnet valve 35 and the passage 24'. The controller arm 15 will be moved in a counter-clockwise direction, first connecting the

motor armature to the motor supply circuit 80 85

45 and then gradually cutting out the connections of the resistance 18-19. The upward movement of the piston rod 13 will this

time produce an upward motion of the piston rod 29 at the controlling valve 20 so as to establish a balance between the position 90

of the controller arm 15 and the position of the scale beam 26 at which the controller arm will be arrested from further movement.

The operation of my improved electro- 95

magnet valve will now be explained. If at any time the voltage of the supply circuit should fail (the abnormal condition selected for purposes of illustration), the valve mag- 100

nets winding 36 will be deenergized and the piston 37 will drop to a position at which the passage 23 is closed, the piston 38 will drop to a position at which the passage 40 is

opened and the passage 24 is closed, and the piston 39 will drop to a position such that 105

the passage 41 is opened. This will cause pressure to be applied to the upper side of the piston 12 through the passage 40, the electromagnet valve 35, and through the

passage 23' which is partly opened. The lower side of the piston 12 will be connected to exhaust through the passage 24', the pas- 110

sage 41 and the passage 43. The above condition will be established at all times in case the valve magnet 36 is deenergized irrespec- 115

tive of the position of the pistons 21 and 22 of the pressure controlling valve 20. It is to be understood that the pistons 21 and 22 of the pressure controlling valve have nor- 120

mally a limited movement such that they will normally never close the passages 40 and 41. The motor controller will thereby be operated so as to disconnect the motor armature 16 from the supply circuit and re- 125

insert all of the resistance 18-19. When the abnormal condition of the supply circuit has ceased, the valve magnet 36 will be en- 130

ergized to raise the pistons 37, 38, and 39 to the positions shown in the drawing, there- 135

by restoring full control of the pressure ac- 140

tuated device 10 to the pressure controlling valve 20.

In accordance with the provisions of the patent statutes, I have described the principle of operation of my invention, together with the apparatus which I now consider to represent the best embodiment thereof, but I desire to have it understood that the apparatus shown is only illustrative and that 10 the invention can be carried out by other means.

What I claim as new and desire to secure by Letters Patent of the United States, is:

1. The combination with a pressure actuated device of a pressure controlling valve for admitting pressure to and exhausting pressure from the said device, means automatically operated in response to a predetermined condition connected to the said 20 valve for operating the same, fluid passages between the valve and the pressure actuated device, and an electro-magnetically actuated valve governing the passages to admit pressure to and exhaust pressure from 25 the said device independently of the said pressure controlling valve and thereby operate the pressure actuated device independently of the said means.

2. The combination with a pressure actuated device of a pressure controlling valve for admitting pressure to and exhausting pressure from the said device, means automatically operated in response to a predetermined condition connected to the said 35 valve for operating the same, connections between the said device and the said valve for returning the valve from its operated to its original position to thereby limit the operation of the said device, fluid passages 40 between the valve and the pressure actuated device, and an electro-magnetically controlled valve in the said passages for admitting pressure to and exhausting pressure from the pressure actuated device independently of the pressure controlling valve.

3. The combination with a member automatically operated in response to a predetermined condition, of a motor controller, 50 a pressure actuated device for operating the same, a pressure controlling valve for admitting pressure to and exhausting pressure from the pressure actuated device, connections between the said member, the said controller and the said valve for operating the said valve in one direction to cause an

operation of the pressure operated actuated device and to return the said valve as the controller is operated, and an electromagnetically controlled valve controlled responsive to abnormal conditions in the motor circuit for independently admitting pressure to and exhausting pressure from the pressure actuated device to effect the return of the motor controller to initial position.

4. The combination with a member automatically operated in response to a predetermined condition, of a motor controller, a fluid pressure actuated device comprising a cylinder and piston for operating the controller, a fluid pressure controlling valve for the fluid pressure actuated device, link mechanism connecting the said member, the said valve and the said controller for operating the valve in one direction in response to the operation of the member and for returning the valve in response to the subsequent operation of the controller, fluid passages between the said valve and the cylinder of the fluid pressure actuated device, and an electromagnetically controlled valve in the said passages adapted when de-energized to admit fluid under pressure through the said pressure controlling valve to one side of the said piston and exhaust the fluid from the other side of the piston through the pressure controlling valve to cause the fluid pressure actuated device to return the motor controller to initial position independently of the control by the said fluid pressure controlling valve.

5. The combination with a pressure actuated device, of a pressure controlling valve and an electromagnetically actuated valve, each operable between two positions for admitting pressure to and exhausting pressure from the said device, means automatically operated in response to a predetermined condition mechanically connected to the 100 said pressure controlling valve for operating the same, and fluid passages connecting the said device, the said valves, and a source of fluid pressure whereby the electromagnetic valve in one position permits the pressure controlling valve to control the operation of the pressure actuated device and in the other position independently controls the operation of the said device.

In witness whereof, I have hereunto set 110 my hand this 26th day of October, 1920.

CLAUDE C. RUNNER.
